United States Patent Office

Des. 232,105
Patented July 16, 1974

232,105

ANIMAL SCRATCHING DEVICE

Franciscus J. Claassen, 270 Ridgeway St.,
Philadelphia, Pa. 19116

Filed Nov. 8, 1972, Ser. No. 304,796

Term of patent 14 years

Int. Cl. D30—99

U.S. Cl. D30—40

FIG. 2

FIG. 1

FIG. 4

FIG. 3

FIG. 5

FIG. 6

FIG. 1 is a perspective view of an animal scratching device showing my new design.

FIG. 2 is a top plan view thereof.

FIG. 3 is a bottom plan view thereof.

FIG. 4 is a right side elevational view, the opposite side being a mirror image thereof.

FIG. 5 is a front elevational view thereof.

FIG. 6 is a rear elevational view thereof.

I claim:

The ornamental design for an animal scratching device, as shown and described.
